Patented Aug. 20, 1912.

UNITED STATES PATENT OFFICE.

MARINUS REÝNGOUDT, OF HASBROUCK HEIGHTS, NEW JERSEY.

LIFE-SAVING APPARATUS FOR SUBMARINES.

1,036,150.

Specification of Letters Patent. Patented Aug. 20, 1912.

Application filed March 7, 1912. Serial No. 682,178.

To all whom it may concern:

Be it known that I, MARINUS REÝNGOUDT, a subject of the Dutch Monarchy, and a resident of Hasbrouck Heights, Bergen county, 5 New Jersey, have invented certain new and useful Improvements in Life-Saving Apparatus for Submarines, of which the following is a specification.

This invention relates to improvements in 10 life saving apparatus for submarines and the object of the invention is to provide easily operated means whereby the crew of a submarine may quickly leave the same and escape in time of danger.

15 To this end the invention is embodied in an apparatus in the form of a life saving boat adapted to be secured within the hull of a submarine in such a manner that it can be reached quickly by the crew and operated 20 from the inside to detach it from the submarine.

The invention will be more fully understood from the following specification while reference is had to the accompanying drawing in which—

Figure 1 is a plan view of a submarine equipped with my life saving boat. Fig. 2 is a vertical sectional view of the life boat taken on the line 2—2 of Fig. 3, and Fig. 3 30 is a transverse sectional view of the boat taken on the line 3—3 of Fig. 2.

Submarines are usually provided with one or more safety chambers in which the crew may find refuge in time of accidents. Preferably I propose to utilize one or more of 35 these chambers to form a cradle or support for my life boat so as to avoid the construction of a special space for the boat.

Referring to Fig. 1 the numeral 4 represents 40 a submarine and 5 is the life boat of which there may be more than one located in any suitable position but preferably in or near the upper portion of the submarine to facilitate the escape of the boat.

45 Referring to Figs. 2 and 3 the numeral 6 denotes the shell of the submarine which is provided with an opening 7 through which the life boat is let into the submarine and through which opening the boat leaves the 50 latter. Within the submarine there is formed a boat chamber 8 inside a cradle 9. This boat chamber may be one of the aforementioned safety chambers or it may be a specially 55 provided space in the submarine. The cradle comprises the shell 9 and the supporting ribs 10 and is provided with a groove 11 for the

reception of the keel of the boat 5. 12 is an anteroom leading from the interior of the submarine and into the boat chamber 8. A door 13 is operable from the inside of the 60 room 12 to close the latter.

The life boat 5 is made in any suitable form and the detailed construction thereof is not material to this invention. It comprises a shell 14 and is provided with an 65 overhanging flange 15 adapted to rest upon a ledge formed inside a guiding flange 16 of the submarine. A gasket 17 is interposed between the flange 15 and the submarine to close the opening 7 watertight. 70 In the top of the boat I provide port holes 18 which are closed by glass covers 19 in the usual manner. The one end of the boat is provided with a manhole 20 which is closed by a cover 21 operated from the inside of the 75 boat. In order to secure the boat to the submarine I provide means operable from the inside of the boat. In this instance and as a matter of illustration only I provide bolts 22 which are in threaded engagement with 80 bosses 23 on the cradle 9. Suitable bearings 24 are provided for the bolts. Other bolts 25, 25 are threaded into the shell 14 of the boat and each bolt is provided with a head 26 which bears against the shell of the 85 cradle 9.

27 is a pipe which leads from the outside of the submarine in any convenient manner so as to conduct water into the boat chamber 8.

90 28 is a valve in the pipe 27 and it has a valve stem in engagement with the lower end of a bolt 29 which is threaded into a boss 30 similar to the bosses 23. The valve 28 is hung in the pipe 27 from a cross piece 31 by the springs 32 which tend to open the valve. The latter is closed by screwing the bolt 29 down until the valve is seated.

95 33 is an air pipe to permit the escape of the air within the boat chamber by opening 100 the valve 34.

35 is an air vent in the life boat. 36 is the keel of the latter which enters the aforementioned groove 11.

37, 37 are side bosses to aid in properly 105 centering the boat and space the same within the boat chamber.

It will be observed that there is a space all around the life boat within the boat chamber. This space is unobstructed except for the bosses and bolts mentioned.

110 When the crew wishes to escape, the men

first enter the room 12 and close the door 13 behind them, thus preventing water from entering the room, the usual danger in submarine work being the danger of drowning of the crew. The door 13 serves, however, also another purpose, namely that of cutting off communication between the interior of the submarine and the boat chamber and whereby the latter is enlarged so 10 to speak. The man hole 20 is of course open and the crew can then enter the life boat and close the man hole behind them by the cover 21. Next the men set to work to unscrew the bolts 22 to free them from 15 the cradle 9, but they do not entirely withdraw these bolts as that would leave uncovered openings in the bottom of the life boat as will be understood. At the same time the valve 28 is opened by loosening 20 the bolt 29 and water now passes into the boat chamber and fills the latter to float the life boat so that the boat can ascend in the water to the surface thereof, where the men will open the portholes and escape. 25 The air in the boat chamber escapes before the water by opening the valve 34 and to further assist in the floating of the life boat the bolts 25 are operated outwardly to cause the heads 26 to press against the 30 cradle 9. It will thus be seen that I have provided very simple and easily operated means to enable the crew to escape. The water commences to fill the boat chamber and will overflow into the room 12 from 35 which it cannot escape because of the door 13, thus the volume of water within the boat chamber is increased and the boat is quickly freed from the submarine.

Changes in the detailed construction 40 shown and described may of course be made, and I claim all such changes as properly come within the principle of the invention and the scope of the appended claims.

I claim:—

45 1. The combination with a submarine having an opening in its shell, of a cradle beneath said opening forming a boat chamber, a life boat adapted to be contained within said chamber and to close the said 50 opening, said chamber having an anteroom formed at its one end and normally in communication with the interior of the submarine, means for cutting off communication between the interior of the submarine 55 and the said anteroom and between the lat-

ter and the interior of the said boat, means for supplying water to the anteroom and the boat chamber to float the boat and means for establishing communication between the boat chamber and the outside of 60 the submarine to permit the air in the boat chamber to escape.

2. The combination with a submarine, of a cradle in the same forming a boat chamber, a life boat adapted to be contained 65 within the said chamber and whereby a space is formed beneath and to the sides of the boat inside the cradle, said chamber having an anteroom formed at its one end and normally in communication with the 70 interior of the submarine, means for cutting off communication between the interior of the submarine and said anteroom and between the anteroom and the interior of the said life boat, bolts carried by the boat for 75 securing the same to the said cradle, other bolts carried by the boat and adapted to be operated to exert a pressure against the cradle to help freeing the boat therefrom, all of the said bolts being operable from the 80 inside of the said boat, a pipe for supplying water to the said anteroom and space formed around the boat to float the same, a valve in said pipe and means for operating said valve from the inside of the boat. 85

3. The combination with a submarine, of a cradle in the same forming a boat chamber, a life boat adapted to be contained within said chamber whereby a space is formed beneath and around said boat inside said cradle, means for securing the boat to the submarine, a water pipe located in the bottom of said cradle and communicating with the space aforesaid for supplying water thereto, a valve in said pipe, a 95 bolt for closing said valve, springs for automatically opening the valve when said bolt is withdrawn to admit water to the said space and a pipe carried by the said boat and communicating with the said space at 100 the top thereof to permit the air in the latter to escape before the water admitted by the aforesaid pipe.

Signed at New York, N. Y. this 4th day of March 1912.

MARINUS REYNGOUDT.
